UNITED STATES PATENT OFFICE.

THOMAS GILBERT GILBERTSON, OF GLASGOW, SCOTLAND.

BOOT-TREE.

1,232,529.

Specification of Letters Patent.

Patented July 10, 1917.

Application filed January 10, 1917. Serial No. 141,640.

To all whom it may concern:

Be it known that I, THOMAS GILBERT GILBERTSON, of 91 St. Vincent street, in the county of the city of Glasgow, Scotland, 5 master bootmaker, have invented certain new and useful Improvements in and Connected with Boot-Trees, of which the following is a specification.

My invention relates to improvements in 10 and connected with boot-trees and refers to that class in which the front and heel sections thereof have arranged between them jointed links or toggles, the movement of which operates the different sections of the 15 tree, and the object of my invention is to simplify the construction and manipulation of such, and thereby minimize the cost of manufacture, and at the same time give greater rigidity to the parts and obtain a 20 uniform pressure on the tree, and further to tree the heel of the shoe or boot as effectively as the front thereof, which is very essential for retaining a good shape of the boot or shoe.

25 In order that my invention may be properly understood and readily carried into effect, I have hereunto appended one sheet of drawings, of which—

Figure 1 is a side view of the boot-tree 30 made in accordance with and embodying my invention applied to a boot and illustrating the said tree in the expanded maximum position.

Fig. 2 is a similar view of the boot-tree 35 also applied to the boot in the collapsed position.

Fig. 3 is a similar view to Fig. 1 of the boot-tree embodying a modification in respect of the joint.

40 Fig. 3^a is a front view of part of the stem or rod in order to illustrate its hinge formation.

Fig. 4 is a similar view to Fig. 2 illustrating the boot-tree collapsed, all hereafter 45 more fully referred to and described.

Referring to the drawings, A is the forepart of the boot-tree which is solid, and A has a rear end face A¹ which is inclined upwardly and rearwardly at an obtuse angle to 50 the base of the forepart, while B is the heel part, the two sections A and B being connected together at their upper surface by a hinge C, one of the plates C¹ of the hinge covering the whole face of the upper side 55 of the toe-piece while the other plate C² covers the whole upper face of the heel-piece.

A² is the longitudinal slot in the face A¹ of the toe piece A. D and E are the two arms of the joint or toggle, one end of D being pivoted to the toe-part A at the bottom of the slot A² at D¹, while the other end is pivotally connected to the stem or rod F by a cross-pin K which stem or rod passes up through the slot in the toe-piece A of the tree and through an opening in the hinge 60 plate C¹ terminating in a ring F¹, the other joint member E having one of its ends pivoted to the heel piece B at the bottom of the angled slot H at E¹, while the other end is also pivotally connected to the stem or rod 70 F by the cross pin K. J are recesses formed in the inner ends of certain of the arms which greatly assist in allowing the arms to come together when withdrawing the tree.

In Fig. 1 the arm E is provided with a 75 recess J, this recess appearing also in Fig. 2, while in the form shown in Fig. 3 the arms D and F are provided with recesses J, but the arm E does not have such a recess.

When to be used, the tree, which is not 80 in the expanded position, is placed in the boot or shoe, as in Fig. 2, and the rod or stem F pushed down by the ring F¹, and in so doing the arms D and E become extended and thereby throw or push forward the fore 85 or toe part A of the tree, and simultaneously therewith throw or push back the heel portion B of the tree until it assumes the position illustrated in Fig. 1.

Again when it is desired to withdraw the 90 boot-tree, the stem or rod F is pulled in an upward direction by the ring F¹ and in so doing the arms D and E come together, the recess J in the arm E materially aiding this, the arm D resting or bedding itself in the 95 slot A² whereby the abutting surfaces of the sections A and B are capable of being brought together until they lie close one with the other in the collapsed state as shown in Fig. 2, thereby allowing the tree to be readily and easily removed from the boot or shoe.

In the modification illustrated in Figs. 3 and 4, the reverse action takes place, that is by pulling up or raising the stem or rod F by the ring F¹, the arms D and E become 105 extended and the boot is treed as shown in Fig. 3, and by pushing down the rod or stem F, the tree is released as shown in Fig. 4, and can be readily withdrawn. In this case the upper part of the stem F is hinged 110 as shown so that when the tree is in the boot, the stem, is folded over or turned down, and

so is out of the way, as shown in dotted line, Fig. 3. In this case there are two slots in the toe-piece of the tree, the rod F bedding in A² and the arm D in slot A³.

5 Claims:

1. A boot or shoe tree comprising in combination a toe or forepart and a heel or rear part, said forepart having a rear end face inclined upwardly and rearwardly at an obtuse angle to the base of the forepart, said forepart and said rearpart being hinged together at their upper ends, said forepart having a deep longitudinal slot in the rear face thereof and said rearpart having an angled slot in the forward face thereof opposite the slot in said forepart, links pivotally connected together and pivoted one to each of said parts, and a stem or rod pivoted to said links at the point of connection between them and forming a toggle therewith, said rod lying for at least a part of its length within the slot in said forepart and the link connected to said rearpart extending into the angled slot thereof.
- 10 2. A boot or shoe tree comprising in combination a toe or forepart and a heel or rear part, said forepart having a rear end face inclined upwardly and rearwardly at an obtuse angle to the base of the forepart, said forepart and said rearpart being hinged together at their upper ends, said forepart having a deep longitudinal slot in the rear face thereof and said rearpart having an angled slot in the forward face thereof opposite the slot in said forepart, links pivotally connected together and pivoted one to each of said parts to form a toggle, and a stem or rod pivoted to said links at their common pivot, said rod lying for at least a part of its length within the slot in said forepart and the link connected to said rearpart extending into the angled slot thereof.
- 15 3. A boot or shoe tree comprising in combination a toe or forepart and a heel or rear part, said forepart having a rear end face inclined upwardly and rearwardly at an obtuse angle to the base of the forepart, said forepart and said rearpart being hinged together at their upper ends, said forepart having a deep longitudinal slot in the rear face thereof and said rearpart having an angled slot in the forward face thereof opposite the slot in said forepart, links pivotally connected together and pivoted one to each of said parts to form a toggle, and a stem or rod pivoted to said links at their common pivot, said rod lying for at least a part of its length within the slot in said forepart and the link connected to said rearpart extending into the angled slot thereof.
- 20 4. A boot or shoe tree comprising in combination a toe or forepart and a heel or rear part, said forepart having a rear end face inclined upwardly and rearwardly at an obtuse angle to the base of the forepart, said forepart and said rearpart being hinged together at their upper ends, said forepart having a deep longitudinal slot in the rear face thereof and said rearpart having an angled slot in the forward face thereof opposite the slot in said forepart, links pivotally connected together and pivoted one to each of said parts to form a toggle, and a stem or rod pivoted to said links at their common pivot, said rod lying for at least a part of its length within the slot in said forepart and the link connected to said rearpart extending into the angled slot thereof.
- 25 5. A boot or shoe tree comprising in combination a toe or forepart and a heel or rear part, said forepart having a rear end face inclined upwardly and rearwardly at an obtuse angle to the base of the forepart, said forepart and said rearpart being hinged together at their upper ends, said forepart having a deep longitudinal slot in the rear face thereof and said rearpart having an angled slot in the forward face thereof opposite the slot in said forepart, links pivotally connected together and pivoted one to each of said parts to form a toggle, and a stem or rod pivoted to said links at their common pivot, said rod lying for at least a part of its length within the slot in said forepart and the link connected to said rearpart extending into the angled slot thereof.

stem or rod pivoted to said links at their common pivot, said rod lying for at least a part of its length within the slot in said forepart and the link connected to said rearpart extending into the angled slot thereof, certain of the parts forming said toggle and rod being cut away near the central pivot of the toggle to facilitate the folding of the tree.

3. A boot or shoe tree comprising in combination a toe or forepart and a heel or rear part, said forepart having a rear end face inclined upwardly and rearwardly at an obtuse angle to the base of the forepart, said forepart and said rearpart being hinged together at their upper ends, said forepart having a deep longitudinal slot in the rear face thereof and said rearpart having an angled slot in the forward face thereof opposite the slot in said forepart, links pivotally connected together and pivoted one to each of said parts to form a toggle, and a stem or rod pivoted to said links at their common pivot, said rod lying for at least a part of its length within the slot in said forepart and the link connected to said rearpart extending into the angled slot thereof.

4. A boot or shoe tree comprising in combination a toe or forepart and a heel or rear part, said forepart having a rear end face inclined upwardly and rearwardly at an obtuse angle to the base of the forepart, said forepart and said rearpart being hinged together at their upper ends, said forepart having a deep longitudinal slot in the rear face thereof and said rearpart having an angled slot in the forward face thereof opposite the slot in said forepart, links pivotally connected together and pivoted one to each of said parts to form a toggle, and a stem or rod pivoted to said links at their common pivot, said rod lying for at least a part of its length within the slot in said forepart and the link connected to said rearpart extending into the angled slot thereof.

5. A boot or shoe tree comprising in combination a toe or forepart and a heel or rear part, said forepart having a rear end face inclined upwardly and rearwardly at an obtuse angle to the base of the forepart, said forepart and said rearpart being hinged together at their upper ends, said forepart having a deep longitudinal slot in the rear face thereof and said rearpart having an angled slot in the forward face thereof opposite the slot in said forepart, links pivotally connected together and pivoted one to each of said parts to form a toggle, and a stem or rod pivoted to said links at their common pivot, said rod lying for at least a part of its length within the slot in said forepart and the link connected to said rearpart extending into the angled slot thereof.

In witness whereof I affix my signature.

THOMAS GILBERT GILBERTSON.
